UNITED STATES PATENT OFFICE.

JAMES C. HARPER, OF RECTOR, ARKANSAS.

APPARATUS FOR MIXING GAS OR VAPOR.

No. 797,278.

Specification of Letters Patent.

Patented Aug. 15, 1905.

Application filed November 5, 1904. Serial No. 231,568.

To all whom it may concern:

Be it known that I, JAMES C. HARPER, a citizen of the United States, residing at Rector, in the county of Clay and State of Arkansas, have invented a new and useful Apparatus for Mixing Gas or Vapor, of which the following is a specification.

This invention relates to mechanism employed for the mixing of gas or vapor, and is designed more especially to produce an explosive mixture employed for internal-combustion engines.

One object of the invention is to provide a novel form of mixer for thoroughly intermingling carbureted air and atmospheric air in advance of its entrance to the explosion-chamber of the engine or delivery to other points of consumption.

With this and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a longitudinal sectional view of an air and gas mixer constructed in accordance with the invention. Fig. 2 is a transverse section of the same on the line 2 2 of Fig. 1.

Similar numerals of reference are employed to indicate corresponding parts throughout both figures of the drawings.

In carrying out the invention I employ a casing 25, within which is a ring 26, preferably concentric with the casing, and between the ring and casing extend partitions 27, that divide the annular space into two separate chambers, to one of which air is admitted through an opening 28, the opposite opening 29 being connected to the gas-supply pipe 23. The ring 26 is provided with a large number of ports 30, and its inner surface forms a seat for the reception of a rotary valve 31, that is provided with two sets of ports 32 and 33,

which may be brought into alignment with the ports 30, and thus admit both air and gas to the hollow central portion of the valve. One end of the valve is closed and its opposite end is provided with an opening 36', that is at all times in communication with an opening 37, through which the mingled air and gas passes. The ports 32 33 are so disposed with relation to the ports 30 that as the ports 32 are fully open the ports 33 will be fully closed, and vice versa, and said valve is preferably connected by an arm 38' to an engine-governor when the device is to be operated automatically. If the mixed air and gas discharging through the opening 37 is too rich in carbon, the lever 38 is moved until the ports 32 are partially closed and the ports 33 partly opened, admitting a greater or less quantity of air, and if the arm 38 is connected to the engine-governor the mechanism is so arranged that in the event of the speed exceeding a predetermined point the ports 33 will be opened wider than usual and the gas diluted in order to lessen its force and reduce the speed of the engine, and in some cases the gas may be wholly cut off and air only admitted to the explosion-chamber.

Having thus described the invention, what is claimed is—

1. In an air and gas mixer, a casing having independent air and gas inlets, a ported ring within the casing, partitions dividing the space between the ring and casing into two chambers, a hollow ported valve arranged within said ring and forming a chamber in which the entering volumes of air and gas are intermingled, said valve being revolvably adjustable to alter the relative effective areas of the ports through which the gas and air may pass into the mixing-chamber, and an outlet leading from said mixing-chamber.

2. The combination in an air and gas mixer, of a casing, a ported ring disposed concentrically within said casing, partitions extending between the ring and casing and dividing the space between the two into two chambers, one of which is open to an air, and the other to a gas supply, a hollow valve disposed within the ring and provided with a plurality of ports which may be adjusted

relatively to the ring-ports, the interior of the valve forming a mixing-space for the air and gas entering thereinto, one end of said valve being closed, and the other being provided with an opening for the discharge of the mingled air and gas, and an operating-lever secured to the closed end of the valve.

In testimony that I claim the foregoing as my own I have hereto affixed my signature in the presence of two witnesses.

JAMES C. HARPER.
